UNITED STATES PATENT OFFICE.

HENRY BAUM, OF CLEVELAND, OHIO.

COMPOUND TOOL.

Application filed December 14, 1922. Serial No. 606,831.

To all whom it may concern:

Be it known that I, HENRY BAUM, citizen of the United States, residing at Cleveland, in the county of Cuyahoga and State of Ohio, have invented certain new and useful Improvements in Compound Tools, of which the following is a specification.

This invention relates to compound tools of the pocket knife type, and it provides a tool which can be used as a pen knife or the like, as a scraper, or as a cigar cutter, and the feature of the tool is that use may be made of old razor blades, one of which can be set into a holder provided for the purpose, and which can be renewed from time to time by inserting other old or discarded blades.

The device will be more fully understood from the following description and the accompanying drawings in which Fig. 1 is a plan of the tool in folded position. Fig. 2 is a plan with the handle unfolded for use as a knife. Fig. 3 is a section on the line 3—3 of Fig. 1. Fig. 4 is a plan of the tool with the handle partly closed. Fig. 5 is a plan showing the blade holder swung out and the parts engaged for use as a scraper. Fig. 6 is a section on the line 6—6 of Fig. 5.

The handle consists of two parts 6 and 7 pivoted together at 8 with a knuckle joint so that the ends 9 of the section stop against each other when the handle is unfolded, shown in Fig. 2. This affords a good grip for the hand when the device is used as a knife.

Each section of the handle is made of a piece of folded sheet metal, the fold extending lengthwise with the handle. The section 6 is cut away as indicated at 10 to form a rectangular recess extending along the inner part of the free end. The blade holder is indicated at 11, and consists of a piece of sheet metal folded upon itself, the outer edges 12 being spaced apart to receive a blade 13 therebetween, and the inner edge being flattened or depressed as indicated at 14, to enter between the opposite sides of the handle section 6, a shoulder being produced at 15, on each side. The holder 11 is pivoted at 16 between the folds of sides of the handle section 6 at the end thereof, and the end of the handle is slotted at 17 to permit the blade holder to be swung around on its pivot to a position at a right angle to the length of the handle, shown in Fig. 5, the edge of the rib 14 stopping against the

end of the slit 17, as shown at 18, when the blade holder is fully swung out.

The section 7 of the handle has a hole 19 through the same, and the edges of the fold 60 are spread apart, as indicated at 20, so that the edge of the blade 13 may enter between the folds, as shown in Figs. 1 and 4. By inserting a cigar tip through the holes 19 the blade will clip the same in an obvious 65 manner. The ends of the folds of the section 7 are also spread or separated, as indicated at 21 so that when the blade holder is swung out to right angle position, as shown in Fig. 5, the handle section 7 may be swung in behind the same, as shown, a slit 22 at the fold of the handle section permitting the blade holder to enter between the lips 21 and stop against the shoulder 23 at the end of the slit. The edge of the blade is then presented outwardly in line with the handle, and the device may be used as a scraper, putty knife, or the like.

When the handle is folded as shown in Fig. 1, the edge of the blade is covered and 80 protected. The handle may be swung open as shown in Fig. 2, and the blade used as a knife. Or the parts may be swung to a position shown in Fig. 5 as above described and the device used as a scraper.

The blade 13 is inserted in the holder 11 by sliding the same endwise, the blade being preferably of a type having a folded clip 23 secured to its rear edge, and when the blade is slid in, this clip is engaged behind lips 24 extending along the outer edge of the holder, and, furthermore, the holder has a lip 25 struck in at one end of the channel formed by the two sides, which prevents the blade being slid out of that end. Accordingly the blade can only be removed by swinging the holder to the position shown in Fig. 5 which uncovers the open end of the holder and permits the blade to be pulled out.

I claim:

1. A compound tool comprising a handle consisting of pivoted sections, a blade holder pivoted to the free end of one section to swing in or out and a blade fitted in the 105 holder, the other section of the handle being foldable to engage its free end with the holder when the latter is swung out.

2. A scraper comprising a handle having a recess at one end, a blade holder pivoted to said end of said handle and arranged to swing into said recess to engage

its shoulders with the edges of said handle and arranged to swing out of said recess, and a blade slidable endwise into and out of the holder, said holder having means to prevent the blade sliding out of the holder except when swung out of said recess.

3. A compound tool comprising a handle consisting of pivoted sections, a blade holder with a blade therein, said blade holder being pivoted to the free end of one section 10 and adapted to swing into rigid position in

a recess of said section with its edges parallel with said section, or to be swung out perpendicular to said section and into engagement with the free end of the other section. 15

In testimony whereof, I affix my signature in presence of two witnesses.

HENRY BAUM.

Witnesses:

JOHN A. BAUMHARDT,
BESSIE POLLAK.
